COMBINED FILTER DISPENSER DISPLAY AND HOLDER UNIT

Alex J. Weinstein, Mount Vernon, N. Y., assignor to
The Ednalite Optical Company, Inc., Peekskill, N. Y.,
a corporation of New York

Application September 21, 1954, Serial No. 32,379

Term of patent 7 years

(Cl. D80—9)

FIG. 1

FIG. 2

FIG. 3

To all whom it may concern:

Be it known that I, Alex J. Weinstein, a citizen of the United States, residing at 182 Commonwealth Avenue, Mount Vernon, in the county of Westchester and State of New York, have invented a new, original, and ornamental Design for a Combined Filter Dispenser Display and Holder Unit, of which the following is a specification, reference being had to the accompanying drawing, forming part thereof.

In the drawing

Fig. 1 is a front elevational view of a combined filter dispenser display and holder unit, showing my new design;

Fig. 2 is a side elevational view thereof; and

Fig. 3 is a rear elevational view.

I claim:

The ornamental design for a combined filter dispenser display and holder unit, substantially as shown.
